INVENTOR:

David Walker,

BY Draket & Co. ATTY'S.

UNITED STATES PATENT OFFICE.

DAVID WALKER, OF NEWARK, NEW JERSEY.

DESIGN FOR A STAIR-BUTTON.

SPECIFICATION forming part of Design No. 18,950, dated March 5, 1889.

Application filed December 3, 1888. Serial No. 292,576. Term of patent 14 years.

To all whom it may concern:

Be it known that I, DAVID WALKER, a citizen of the United States, residing at Newark, in the county of Essex and State of New Jersey, have invented and produced a new and original Design for a Stair-Button; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a front elevation of a stair-carpet button showing my design, and Fig. 2 is a section of the same taken on line *x*.

The leading feature of my design consists in a stair-carpet button which is triangular taken transversely or in cross-section, one of the sides being convex and displaying from the straight center a continuous series of ornamental members.

In the drawings, *A* indicates the longitudi-

nally-straight member of the ornamented convex side of the button, and *b b* the tapering ends, which display beaded ornamental members *c d e f*, which present to the eye an irregular tapering outline at each side of the center of said button, as distinguished from a straight inclination simply rounded at the ends.

What I claim is—

The design for a stair-carpet button herein shown and described, the same consisting of a triangular stair-button, one of the sides of which is convex and its tapering opposite ends displaying ornamental beads *c d e f*, presenting an irregular outline, as set forth.

In testimony that I claim the foregoing I have hereunto set my hand this 10th day of November, 1888.

DAVID WALKER.
